UNITED STATES PATENT OFFICE.

JOHN H. CLEGG, OF SUFFERN, NEW YORK.

DISPENSING DEVICE FOR COLLAPSIBLE CONTAINERS.

Application filed July 7, 1922. Serial No. 573,296.

To all whom it may concern:

Be it known that I, JOHN H. CLEGG, a citizen of the United States, and a resident of Suffern, in the county of Rockland and State of New York, have invented a new and Improved Dispensing Device for Collapsible Containers, of which the following is a full, clear, and exact description.

This invention relates to dispensing devices and has particular reference to an apparatus for dispensing goods packaged in collapsible containers, such as tubes of tooth paste, shaving cream, or the like.

As an object the invention contemplates an apparatus for conveniently housing, supporting and operating upon a collapsible tube to successively effect the discharge of a uniform requisite quantity of the contents thereof in order to eliminate waste by over-feeding of the contents and effect a saving of time due to loss or misplacement of the tube.

As a further object the invention contemplates in a device of the character described a closure for the discharge outlet and means operable upon the manipulation of the feeding means for opening the closure in advance of the exertion of pressure on the tube for expressing the contents therefrom, said feeding means further operating to close the closure upon its return movement to normal position.

As a still further object the invention contemplates in connection with a device of the character set forth means for successively effecting a uniform pressure on a collapsible tube which is automatically returned to a normal open position after the contents have been entirely discharged whereby to receive and accommodate a fresh tube.

The invention furthermore aims to provide a device of the character described which is comparatively simple in its construction and operation, inexpensive to manufacture and produce and one which is thoroughly reliable and highly efficient in its purpose.

With the above recited and other objects in view, the invention resides in the novel construction set forth in the following specification, particularly pointed out in the appended claim and illustrated in the accompanying drawings, it being understood that the right is reserved to embodiments other than those actually illustrated herein to the

full extent indicated by the general meaning of the terms in which the claims are expressed.

In the drawings—

Figure 1 is a vertical sectional view 60 through a dispensing device constructed in accordance with the invention.

Fig. 2 is a fragmentary horizontal sectional view taken approximately on the line 2—2 of Fig. 1.

Fig. 3 is a view similar to Fig. 1, illustrating the operation of the device.

Fig. 4 is a vertical transverse sectional view taken approximately on the line 4—4 of Fig. 1.

Referring to the drawings by characters of reference, the device comprises a supporting base 10 which is preferably of hollow construction and is provided at its forward lower end with a drip trough 11. A conduit pipe 12 is arranged within the base 10 and is provided at its inner end with an upturned extremity 13 which extends upwardly through the upper wall of the base and is inferiorly threaded as at 14 to receive the threaded discharge nozzle A of a collapsible tube B. From the upturned extremity 13 the conduit tube 12 inclines downwardly and projects through the front wall of the base with the outer end thereof overlying the drip trough 11. An upstanding supporting bracket 15 is provided adjacent the rear of the base and said bracket is provided with superposed forwardly projecting bearing arms 16 and 17. Forceps are provided consisting of a pair of jaws 18 and 19 having pivotal connection and supported by a bolt 20 passing through the aligned ears 21 there- of and the forward end of the bearing arm 16. The jaws 18 and 19 depend from the bracket arm and are disposed at opposite sides of the collapsible tube or container B whereby relative movement thereof toward each other exerts a pressure upon the tube or container for expressing the contents thereof through the nozzle A and into the conduit tube 12. The jaws are respectively provided with upstanding extensions 22 and 23 which constitute actuating elements for effecting the closure of the jaws upon relative movement of the same away from each other. The mechanism for successively effecting relative separation of the extensions 22 and 23 consists of a transverse shaft 24 journaled in the forward end of the upper bearing arm 70

17 and the angle bracket 25 attached thereto. A pair of oppositely disposed cams 26 and 27 are secured to the shaft 24 between the bearing arm and bearing bracket for respective coacting engagement with the extensions 22 and 23 upon turning movement of the shaft 24 in a clockwise direction. The means for turning the shaft comprises a ratchet wheel 28 secured to the shaft 24 and a spring 5 pressed pawl 29 carried by an arm 30 mounted at its inner end for free or independent rocking movement on the shaft 24. A manipulating lever 31 is pivotally connected at its inner end as at 32 to the upper end of the supporting bracket 15. The manipulating lever is provided with a pin or trunnion 33 which operates in an arcuate slot 34 of the arm 30, said slot being disposed concentric to the pivot 32 of the manipulating lever. 10 The conduit tube 12 is provided intermediate its ends with a cut-off valve 35 having an operating handle 36 which is connected by a connecting rod 37 to the manipulating lever 31. A coil spring 38 encircles the pivot 32 15 and engages respectively at its opposite ends with the bearing arm 17 and the lever 31 to normally dispose the lever in its uppermost position against the upper stop or abutment 39. The lower stop or abutment 40 is designed to coact with the lever upon downward movement to limit the downward swinging thereof. Preferably the operating mechanism and collapsible tube are housed by a casing 41 which slides downwardly 20 thereover and rests upon the top wall of the base. The front wall of the casing 41 is vertically slotted upwardly as at 42 from its lower end to receive and accommodate the handle 43 at the outer free end of the manipulating lever 31.

In use and operation of the device the collapsible tube or container B is associated with the device by threading its discharge or outlet nozzle A into the internally threaded upturned inner extremity of the conduit tube 12, said tube lying between the jaws 18 and 19 of the forceps. To express the contents from the tube or container B, the handle 43 of the manipulating lever is pressed 25 downwardly. The pin or trunnion 33 operating in the arcuate slot 34 of the arm 30 permits of an initial movement of the lever without effecting the movement of the arm 30 whereby through the connecting rod 37 30 the handle 36 of the valve 35 will be shifted to open the valve prior to the exertion of pressure by the jaws 18 and 19 on the tube or container B. When the pin 33 engages with the lower end of the slot 34 of the arm 30, the said arm 30 will move downward with the lever until the same coacts with the lower stop or abutment 40. During the movement of the arm 30 by the lever the pawl 29 engaging with the teeth of the

ratchet wheel 28 will turn the shaft 24 a predetermined distance, thereby effecting a relative separation of the extensions 22 and 23 through the medium of the cams 26 and 27. This will effect the advancement of the jaws 18 and 19 toward each other for expressing a predetermined quantity of the contents of the tube or container B through the outlet nozzle and into the conduit tube 12 thereby forcing from the outer exposed end of the conduit tube a quantity of the contents which fills the conduit tube. When the handle 43 is released the manipulating lever will be returned to normal position, thus successively closing the valve 35 and finally effecting a retrograde or counter clock-wise movement of the arm 30 by the engagement of the pin 33 with the upper end of the slot 34. The upward movement of the manipulating arm under the influence of the spring 38 will be arrested by the upper stop or abutment 39. A coil spring 44 encircles the pivot bolt 20 of the forceps with its opposite extremities 45 and 46 respectively engaging the jaws 18 and 19 to effect their relative separation. When the tube or container B has been emptied the high points of the cams 26 and 27 will be disposed in a position to release the extensions 22 and 23 upon the next operation of the manipulating lever 31. When this occurs the spring 44 will function to effect relative separation of the jaws 18 and 19 and the advancement of the extensions 22 and 23 toward each other where they will again coact with the cams for the purpose of successively and gradually effecting their separation and the advancement of the jaws 18 and 19 toward each other after a new or fresh tube or container B has been associated with the device.

From the foregoing it will be appreciated that a simple and inexpensive apparatus has been provided for dispensing the contents of collapsible containers or tubes which effects an economy in the use of the contents thereof.

I claim:

In a device for dispensing substances packaged in collapsible containers, mechanism for exerting a pressure on the container comprising a pair of forceps, a manipulating means operable to successively effect the closure of said forceps, said manipulating means comprising extensions on the forceps jaws, a rotary shaft between said extensions, oppositely disposed cams on the shaft, a ratchet wheel secured to the shaft, an arm loosely mounted on the shaft having a spring pressed pawl, and a manipulating lever engageable with said arm for successively moving the same in opposite directions.

JOHN HINDS CLEGG.
